UNITED STATES PATENT OFFICE

1,956,605

RAILWAY TRACK SWITCH CONTROLLING APPARATUS

Paul F. Willard, Wilkinsburg, Pa., assignor to
The Union Switch & Signal Company, Swiss-
vale, Pa., a corporation of Pennsylvania

Application January 28, 1933, Serial No. 654,047

2 Claims. (Cl. 246—3)

My invention relates to railway track switch controlling apparatus of a type wherein the operations of a railway track switch are at times effected from a point remote from the switch, and are at other times effected from a point adjacent to the switch.

More specifically, my invention relates to apparatus wherein a control lever adjacent a switch, when in a first position, permits normal and reverse operations of the switch to be effected from a remote point, and, when moved to a second or a third position, itself causes the switch to be operated to the normal or the reverse position, respectively.

15 I will describe one form of apparatus embodying my invention, and will then point out the novel features thereof in claims.

The accompanying drawing is a diagrammatic view showing one form of apparatus embodying 20 my invention.

Referring to the drawing, the reference character F designates a railway track switch which is moved from normal to reverse positions and vice versa by some suitable device such for example, 25 as a fluid pressure mechanism M, which is equipped with control magnets designated by the reference characters N, L and R, respectively. Magnets N, L and R are controlled by a lever V¹ which may be located at a remote point such, for example, as an interlocking tower or a train dispatcher's office, and by a lever V³ which may be located adjacent switch F. In conjunction with switch F, mechanism M operates a pair of pole-changing contacts 3 and 5 which become closed 30 in a given position when switch F is moved to its normal position, and which become closed in a second position when switch F is moved to its reverse position.

35 A signal, designated by the reference character S, governs traffic movements over switch F when switch F is in its normal position in which it is shown in the drawing. Signal S is controlled by a lever V² which may be located with lever V¹ in an interlocking tower or a train dispatcher's office. Signal S is also controlled by a switch indication relay K which is energized in the normal or the reverse direction, when lever V³ is in its normal position, according as mechanism M operates switch F to its normal or its reverse position.

40 Lever V¹ has a normal position n, a center position c, and a reverse position r. Lever V¹ operates a contact 1 which is closed when lever V¹ is in its n position or at a point b, or at any other 45 point between position n and point b. Lever V¹

operates a second contact 6 which is closed when lever V¹ is in its r position or at a point d, or at any other point between position r and point d. Lever V¹ also operates a third contact 8 which is closed at either point b or point d, or at any other location between these two points. A fourth contact 13 operated by lever V¹ is closed only when lever V¹ is in its c position.

45 Each of the levers V² and V³ has a normal position m, a left reverse position f, and a right reverse position t. Lever V² operates a contact 12 which is closed only when lever V² is in its right reverse position t. Lever V² may also be provided with a contact which is closed when lever V² is in its f position for controlling other signals 50 for governing traffic movements over switch F. Lever V³ is provided with three contacts 2, 4 and 7, each of which is closed when lever V³ is in its m position only. Lever V³ also operates a contact 14 which is closed when lever V³ is in its f 55 position only, and a contact 15 which is closed when lever V³ is in its t position only.

60 When lever V³ is in its m position, in which it is shown in the drawing, operations of mechanism M for moving switch F to its normal and reverse positions are effected by lever V¹ through its control of magnets N, L and R. If lever V¹ is moved to its c position, operations of mechanism M for moving switch F to its normal and reverse positions can be effected by lever V³. 65

65 As shown in the drawing, lever V¹ is in its n position, each of the levers V² and V³ is in its m position, and switch F is in its normal position. With lever V¹ in its n position and with lever V³ in its m position, magnet N is energized by a circuit passing from terminal B of a source of current not shown in the drawing, through contact 1 of lever V¹, contact 2 of lever V³, and the winding of magnet N to terminal O of the same source of current. With switch F in its normal 70 position and with lever V³ in its m position, indication relay K is energized in the normal direction by current supplied from terminal B, through contacts 3 and 5 in the normal position, and contact 4 of lever V³ to the winding of relay K. With lever V² in its m position, a circuit for controlling the mechanism of signal S, only a portion of which is shown in the drawing, is open at contact 12 of lever V². Signal S is therefore indicating "stop". 75

80 I will now assume that the leverman or the dispatcher who has charge of levers V¹ and V² desires switch F to be moved to its reverse position. He will therefore move lever V¹ to point d, thereby completing a circuit for energizing mag- 85

net R, passing from terminal B, through contact 6 of lever V¹, contact 7 of lever V³, and the winding of magnet R to terminal O. With lever V¹ at point d, magnet L will also be energized by current passing from terminal B, through contact 8 of lever V¹, and the winding of magnet L to terminal O. With magnets L and R energized, mechanism M will move switch F to its reverse position. Upon the completion of this operation, the leverman will move lever V¹ to its r position, thereby deenergizing magnet L but retaining magnet R in its energized condition. The moving of switch F to its reverse position will cause contacts 3 and 5 to be moved to their second position, which will cause relay K to be energized by current of reverse polarity and open its contact 11 in the circuit for controlling the mechanism of signal S.

If now the leverman should desire to return switch F to its normal position, he will move lever V¹ to point b, thereby completing the circuit previously traced for energizing magnet N, and also completing the circuit previously traced for energizing magnet L. Mechanism M will then move switch F to its normal position. This operation of switch F will cause pole-changer contacts 3 and 5 to be returned to the position in which they are shown in the drawing, and hence relay K will again become energized in the normal direction.

If the leverman should now desire to clear signal S, he will move lever V² to its t position, thereby completing the portion of the circuit for signal S shown in the drawing, which includes contacts 10 and 11 of relay K and contact 12 of lever V². If other conditions are correct for closing the portion of the circuit for signal S not shown in the drawing, signal S will therefore be operated to its proceed position.

I will next assume that all parts of the apparatus are again returned to their normal condition, and that it is then desired that switch F shall be controlled locally for switching movements. The leverman or the dispatcher in charge of levers V¹ and V² will therefore move lever V¹ to its c position in which contacts 8 and 13 of this lever will be closed.

If now a trainman moves lever V³ to its t position, a circuit will be completed for energizing magnet R, passing from terminal B, through contact 13 of lever V¹, contact 15 of lever V³, and the winding of magnet R to terminal O. With contact 8 of lever V¹ closed, magnet L will be energized by its circuit previously traced. With magnets L and R energized, mechanism M will move switch F to its reverse position as previously described. The moving of lever V³ away from its m position causes contact 4 of this lever to be opened, and hence causes indication relay K to become deenergized. The manual movement of switch F by the trainman to its reverse position will therefore have no effect on relay K.

When the trainman desires to return switch F to its normal position, he will move lever V³ to its f position, thus causing a circuit to be completed for magnet N, passing from terminal B, through contact 13 of lever V¹, contact 14 of lever V³, and the winding of magnet N to terminal O. With magnet N thus energized and with magnet L energized as previously described, mechanism M will return switch F to its normal position. Contact 4 of lever V³ will again be open, with lever V³ in its f position, and hence relay K will be deenergized. With relay K de-

energized, contact 10 of this relay will be open, and hence signal S could not be cleared even if lever V² should by mistake be moved to its t position and if contact 11 of relay K were closed.

If now lever V³ is returned to its m position, and if lever V¹ is then moved to its n or its r position, switch F will be operated to its normal or its reverse position, respectively. As previously described, the completion of the movement of lever V¹ from point d to its r position or from point b to its n position will open contact 8 of this lever, and hence magnet L will be deenergized.

If, with lever V¹ in its n or its r position, switch F should by some means be displaced from its normal or its reverse position, the consequent movement of pole changer contacts 3 and 5 will cause relay K to become deenergized. A circuit known as a restoring circuit will therefore be completed for magnet L, passing from terminal B, through contact 9 of relay K, and the winding of magnet L to terminal O. With magnet L thus energized, mechanism M will restore switch F to the position corresponding to which of the magnets N and R is energized.

On account of relay K being controlled by contact 4 of lever V³, contact 13 of lever V¹ could be omitted and lever V¹ could be left in either its n or its r position while switch F is being operated as controlled by movements of lever V³ to its f or its t position. Contacts 14 and 15 of lever V³ would then be connected directly with terminal B instead of with contact 13 of lever V¹. Magnet L would then be energized through contact 9 of relay K, as previously described, while either magnet N or R is energized as controlled by lever V³.

From the foregoing description and the accompanying drawing, it follows that one form of apparatus embodying my invention comprises a switch operated by a fluid pressure mechanism; a three-position lever for controlling the switch from a remote point if a second three-position lever adjacent the switch occupies a normal position; and means controlled by the lever adjacent the switch for moving the switch to its normal or its reverse position according as this lever is moved to a second or a third position, respectively.

Although I have herein shown and described only one form of railway track switch controlling apparatus embodying my invention, it is understood that various changes and modifications may be made therein within the scope of the appended claims without departing from the spirit and scope of my invention.

Having thus described my invention, what I claim is:

1. In combination, a railway track switch, operating mechanism for said switch, a first and a second control lever each of which has a first and a second and a third position, means controlled by said second lever when moved to its third position and by said first lever for controlling said operating mechanism to move said switch to its normal or its reverse position according as said first lever is moved to its first or its second position, and means controlled by said first lever when moved to its third position and by said second lever for controlling said operating mechanism to move said switch to its normal or its reverse position according as said second lever is moved to its first or its second position.
2. In combination, a railway track switch, a normal and a reverse control magnet for con-
